UNITED STATES PATENT OFFICE.

MORRIS MARTIN, OF MALDEN, MASSACHUSETTS, ASSIGNOR TO THE MUNICIPAL SIGNAL COMPANY, OF PORTLAND, MAINE.

ELECTRIC SIGNALING APPARATUS.

SPECIFICATION forming part of Letters Patent No. 487,676, dated December 6, 1892.

Application filed February 20, 1892. Serial No. 422,228. (No model.)

To all whom it may concern:

Be it known that I, MORRIS MARTIN, of Malden, county of Middlesex, State of Massachusetts, have invented an Improvement in Electric Signaling Apparatus, of which the following description, in connection with the accompanying drawings, is a specification, like letters and numerals on the drawings representing like parts.

10 This invention relates to electric signaling apparatus, the object being to distinguish between certain kinds of signals that are received. The transmitting mechanism consists of a multiple signal-transmitter constructed 15 and arranged to transmit a distinguishing impulse in connection with some signals and not others, said impulse for the purposes intended being transmitted at a certain specified time. The receiving apparatus comprises both 20 an instrument like an ordinary telegraph-register that records dot-and-dash signals on a traveling strip of paper and an indicating-signal. It is intended that the register shall respond to all signals and that the indicating- 25 signal shall respond to some signals and not to others, and thereby call especial attention to certain signals received, but not to others. An apparatus of this kind is exceedingly useful for police-signaling purposes where certain signals require an immediate answer and others require no answer whatever.

One object of the present invention is to enable signals containing both dots and dashes, or either of them, to be either especially indicated or not, as required, and in the 30 present invention the operation of the indicating-signal depends upon the condition of the transmitting-current or a change effected therein at a certain moment in or during the 35 transmission of a signal. For instance, if the main circuit is closed at such moment there will be no special indication; but if the main circuit is open at this particular time there will be a special indication, and the condition of 40 the main circuit or any changes therein at all other times during the transmission of a signal will have no effect on the special indicator. As a way of accomplishing this result in accordance with the present invention the receiving instrument or register is provided 45 with a circuit-controller, one member of which

may be carried or moved by some part of the paper-feeding train of the register and the other member of which is operated by an electro-magnet in or controlled by the main 55 circuit, being, for example, the same armature that operates the marker or stylus of the register, and the said members of the circuit-controller are so arranged that they can co-operate only at a given moment in the movement of the register, and only then on the reception of the distinguishing impulse, or one member of the circuit-controller may be driven by an independent train or be moved by an independent motor—*i. e.*, independent 60 of the register—although the controlling-magnet of such train or motor will be governed directly or indirectly by the main circuit. In instances where several main signaling-circuits enter a single central station multiple 65 pen receivers or registers are usually employed for simplicity, and in such event a circuit-controller for the circuit of the indicating-signal is provided for each main signaling-circuit—*i. e.*, if there should be four signaling-circuits then there would be four circuit-controllers. The motor-driven members 70 of said circuit-controllers are herein shown as adapted to be driven by the same motor, and hence are arranged side by side on a 75 shaft, but normally restrained from revolving therewith, and the co-operating members of said circuit-controllers are controlled independently by the pen-controlling magnets, which are in turn controlled by the respective 80 signaling-circuits.

Figure 1 shows in plan view the operating mechanism of a telegraph-register embodying this invention, it being arranged in connection with four circuits, the top portion of the 85 inclosing case being removed to expose the operating parts; Fig. 2, a vertical section of the register shown in Fig. 1, taken on the dotted line *xx*; Fig. 3, a vertical section of the register shown in Fig. 1, taken on the dotted line *yy*; Fig. 4, a detail of one member of one of circuit-controllers; Fig. 5, a diagrammatical view showing the circuit of the 90 four-pen register represented in Fig. 1; Fig. 6, a modified form of register arranged in connection with a single circuit, also showing in diagram the circuits and other instruments 95 100

employed in connection therewith to make a complete apparatus; Fig. 7, another modification showing the register in a metallic circuit and the circuit-controller of the indicating-signal governed by an independent motor, and Fig. 8 another modification to be referred to.

The train of wheelwork, which may be of any suitable construction, is contained in the inclosing case, being normally wound up and provided with an escape-wheel or other suitable regulator b . A stop-lever b' , pivoted at b^2 , has a projection b^3 , which enters a notch in a stop-wheel on one of the shafts of the train. Projecting from said stop lever is a short arm b^4 , having a detent b^5 , which engages the teeth of the escape-wheel. An electro-magnet A' is suitably supported in the inclosing case, the armature a of which is attached to a lever a^2 , pivoted at a' , the upper end of said lever having an outwardly-projecting arm a^3 , which engages the short arm b^4 on the stop-lever and lifts it out of engagement with the stop-wheel to let off the normally wound-up train. The feed-rolls c^2 are driven by the said train of wheel-work to feed the paper forward.

The register herein represented is adapted to be operated or controlled by four separate signaling-circuits, and hence four electro-magnets $g\ g'\ g^2\ g^3$ are arranged side by side or otherwise, the armatures of which are attached, respectively, to the armature-levers $f\ f'\ f^2\ f^3$, pivoted to the rod or bar f^4 , said armature-levers each carrying a stylus e , by means of which the paper is marked with dot-and-dash signals, as the case may be, as usual.

Loosely mounted on the shaft h are four disks h' , of insulating material, each having a projection, as h^2 , which by striking against the outer ends of the armature-levers are held stationary, while the shaft h may rotate within it. Friction-plates are arranged on the shaft h , which bear against the said disks, so that when they are released they will turn with the shaft. A metallic band h^3 is secured to one side or face of the disk h' , against which bears a contact-pen, as h^4 , and mounted on the periphery of the disk at a short distance beyond the projection h^2 is a metallic projection h^5 , which is formed integral with or electrically connected with the band h^3 .

Referring to Fig. 5, four main signaling-circuits 1 2 3 4 are shown, which may include or contain signal-boxes of any suitable construction, said circuits also each containing a receiving-relay, as $r'\ r^2\ r^3\ r^4$, and being represented as metallic circuits the armatures of said relays are attracted. The armature of the relay r' when retracted falls against a contact, to which is connected a branch wire w , which wire includes the coils of the pen-magnet g and is connected to wire w' , which includes the coils of the starting-magnet A' and is connected with one pole of the battery B^2 . The said armature is itself connected

with a wire w^2 , which is connected with the other pole of said battery, so that when said armature retracts it will be seen that the local circuit $w'\ w\ w^2$ is closed, the armatures of the starting-magnet A' and pen-magnet g attracted, thereby letting off the train of the register, and by means of the stylus on the armature-lever of the pen-magnet marking the paper. The armatures of the relays $r^2\ r^3\ r^4$ are connected to the wire w^2 , and when retracted close on contacts connected, respectively, with wires $w^3\ w^4\ w^5$, all of which are connected to the wire w' , and the pen-magnets $g'\ g^2\ g^3$ are respectively included in said wires $w^3\ w^4\ w^5$, so that whichever receiving-relay is effected the starting-magnet A' will operate, and that one of the pen-magnets which is included in the branch wire connected to the contact against which the armature of the effected relay strikes.

The disks h' , which are mounted on the shaft h , are also represented in Fig. 5, said disks being restrained from rotation by the armature-levers of the pen-magnets, as shown, and the pens h^4 , which bear against the metallic side or face of said disks, are connected by wires to the wire u , which is connected to one side of the local battery B^3 , and the armature-levers of the pen-magnets are connected by a wire u' to the other side of said battery, and a bell u^3 or other indicating signal is contained in said local circuit adapted to respond whenever said circuit is closed. Whenever one of the pen-magnets operates, its armature-lever being turned on its pivot releases the disk which it has been holding, permitting it to rotate with the shaft h , and as the disk revolves the projection h^5 thereon passes beneath the end 20 of the armature-lever, and said projection is made of the proper length, so that if the armature is held attracted it will pass beneath the end of the lever without touching; but if at the time that said projection arrives beneath the end of said lever the armature should be retracted or in its retracted position a suitable contact is made, whereby the local circuit of the battery B^3 is closed and the bell u^3 thereby caused to respond.

The projection h^5 and the end of the armature-lever, as herein represented, constitute the circuit-controller which controls the local circuit. Each disk, it will be seen, is controlled by its own pen-magnet, so that the local circuit containing the bell will be controlled by the several pen-magnets independently. By this arrangement it will be seen that one of the projections h^5 passes beneath the end of the armature-lever at a certain definite time after the register starts, and if at this moment the end 20 of the armature-lever is retained in one position by the main circuit—as, for example, if the main circuit is opened and the armature of the magnet g attracted—the said member 20 of the circuit-controller will not co-operate to effect the local or special signaling-circuit, and the message that is re-

corded on the strip d will be unaccompanied by any special signal or indication. If, however, the main circuit is in the other condition or changed at this moment and the armature of the magnet g thereby retracted, the members $20 h^5$ will co-operate and effect the local circuit, so that the alarm or special signal will be sounded and attention called to the message, which is subsequently recorded on the tape. The engagement of the member 20 with the periphery of the wheel h after the conducting portion h^5 has passed by produces no effect on the local circuit, as said wheel is made of insulating material.

15 It will be seen that the operation of the special signal does not depend on any difference in the character of the currents transmitted, or even on the duration of currents of uniform character, and precisely the same 20 message can be transmitted, if desired, accompanied by the special signal or unaccompanied by it, it being necessary only to maintain the proper condition of the main circuit at the time that the member h^5 passes beneath the member 20, which is immediately 25 after the register starts. The main circuit 3 is shown as containing a number of transmitting brake-wheels $p p^2 p^3$, the one of which marked p will cause the circuit to be broken 30 at the proper moment to transmit the distinguishing impulse or that impulse which causes the members $20 h^5$ of the circuit-controller to co-operate and effect the operation of the indicating-signal, while the other wheels $p^2 p^3$ 35 are not designed to transmit such a distinguishing impulse. The transmitters of the other main circuits will be formed in substantially this same manner.

It is not essential to the invention that the 40 message should be a dot-and-dash message on a traveling strip by a stylus, as any other kind of a message might be used, it being essential only that there should be a motor at the receiving-station to move the member h^5 45 of the circuit-controller with a sufficiently-accurately-timed movement and that the corresponding member 20 should be controlled by the circuit from the transmitting-station by said distinguishing impulse, which will be transmitted at the proper time to cause the member 20 to engage the member h^5 some 50 time during the short interval of time that it is in proper position.

In Fig. 6 a single pen - register is shown 55 wherein the stylus e , which does the marking, is carried by the armature-lever f of an electro-magnet, which likewise serves as the starting-magnet, it having at its end a projection f^20 , which enters a recess in a stop-wheel. 60 The stop-wheel is herein represented as made of insulating material and as having on it a conducting-piece m , which as the stop-wheel revolves comes beneath a projection on the armature-lever. The piece m and projection 65 on the armature-lever in this instance form the members of the circuit-controller of the local circuit containing the battery B^3 and

bell u^3 . The armature of the bell is represented as holding in normal elevated position a drop t , which when released falls on a contact 9 and closes a branch wire 8 around the battery B^3 . The electro-magnet g is in this instance contained in an open ground-circuit, which also contains a multiple signal-transmitter $p p^2 p^3$, arranged to operate or effect 70 substantially the same result in connection with the register herein shown as is effected by the transmitter shown in Fig. 5.

In Fig. 7 a metallic circuit is shown instead of a ground-circuit and the circuit-controller $m f^{20}$ is arranged on and in connection with a motor F independent of the train of the register, said motor F being released by a magnet g , connected in or with the main circuit.

The indicating-signal u^3 is represented as 85 a tap-bell and included in the local circuit containing the battery B^3 .

In Fig. 8, y represents the stop-wheel of the motor, and m the movable member of the operating device for the indicating-signal, it being arranged on the wheel m^2 . In this instance the first change in the circuit starts the train and the member f^{20} is thrown into contact with the wheel m^2 , and if the change is of long duration the circuit by $m f^{20}$ is 90 made, or if any change in the main circuit is made during a predetermined interval of time the same result follows. Thus the initial impulse or the one used to start the train may 95 be used to cause the bell to respond, if desired.

The member m may be of any desired length, so that the interval of time during which the bell can be sounded may be varied, or the same result may be produced by varying the 100 speed of the train. In Fig. 8 the controlling member is shown as comprising nearly one-half the periphery of the wheel m^2 . Thus it will be seen that my invention is easily applied to other forms of multiple-pen or single-pen registers, and I do not desire to limit my invention to the particular construction of parts by which such application is made.

I claim—

1. A signal-receiving instrument comprising 115 a paper-feeding train of wheelwork and an electro-magnet and armature controlled by the transmitting-circuit, combined with a circuit-controller, one member of which is operated by said train of wheelwork and the other member of which is operated by said electro-magnet, substantially as and for the purposes set forth.

2. In an electric signaling apparatus, multiple signal-transmitters at sub-stations constructed and arranged to transmit a distinguishing impulse with some and not with other signals, a message-receiving instrument at the central station and an electric circuit connecting them, an electro-magnetically-operating indicating-signal and circuit-controller for said indicating-signal, one of the members of which is controlled by a magnet effected 125 by the distinguishing impulse and the other 130

member of which is moved by a motor mechanism into position to co-operate with said electro-magnetically-movable member for a short time only, after which co-operation is not possible, whereby the indicating-signal may be sounded with some signals and not others, substantially as described.

3. In an electric signaling apparatus, signal-transmitting instruments at sub-stations and a message-receiving instrument at a central station, and an indicating-signal also at said central station, combined with a plurality of circuit-controllers which control the circuit of said indicating-signal, one of the members of which is operated by a time-train and the other by an electro-magnet, substantially as described.

4. In an electric signaling apparatus, mul-

tiple signal-transmitters at sub-stations combined with a message-receiving instrument at a main station connected in circuit with said transmitters and comprising a paper-feeding train, a starting-magnet, several pen-magnets and markers operated by their armatures, an indicating-signal and circuit therefor, and several independent circuit-controllers for the said circuit, one of the members of which is operated by the train and the other by the said pen-magnets, substantially as described.

In testimony whereof I have signed my name to this specification in the presence of two subscribing witnesses.

MORRIS MARTIN.
